UNITED STATES PATENT OFFICE.

FRANK E. FARNHAM, OF PROVIDENCE, RHODE ISLAND.

COLLAR-SUPPORTER.

No. 896,367.

Specification of Letters Patent.

Patented Aug. 18, 1908.

Application filed April 6, 1908. Serial No. 425,431.

To all whom it may concern:

Be it known that I, FRANK E. FARNHAM, a citizen of the United States, residing at Providence, in the county of Providence and 5 State of Rhode Island, have invented certain new and useful Improvements in Collar-Supporters, of which the following is a specification, reference being had therein to the accompanying drawings.

10 Like reference numerals indicate like parts. Figure 1 is a plan view of my combined bar and lining plates for collar supporters. Fig. 2 is a side elevation of the cupped-up blank to form the ornamental front of my improved 15 lace pin. Fig. 3 is a central longitudinal section of a modified form of my said lace pin. Fig. 4 is a view on an enlarged scale showing said bar and one of the lining plates in side elevation, secured in position within one of 20 said lace pins, whose edges have been rolled over into contact therewith, said lace pin being represented as seen in cross section on line $x-x$ of Fig. 2. Fig. 5 is a similar view on the same enlarged scale, showing a modified 25 form of the bar as secured in position upon the modified form of lace pin illustrated in Fig. 3, said lace pin being shown in cross section on line $z-z$ of Fig. 3 and the lining plate in section on a line coincident therewith. Fig. 30 6 is a plan view of the under side of my improved collar supporter.

My invention relates to collar supporters, adapted to extend transversely of the collar of lace or other soft material for a lady's 35 dress; and it consists of the novel construction and combination of the several parts thereof as hereinafter described and claimed.

In the drawings 1 represents a rigid bar, of any ornamental or other shape desired, at 40 each end of which bar is an integral T-shaped lining plate 2, having its two longitudinal edges preferably convexed slightly, as shown in Fig. 1. Each of the plates 2 may have the two rivet holes 3.

45 In Fig. 2 is illustrated the cupped-up blank of the ornamental front of a lace pin, such as is shown in Figs. 5, 6 and 8 of Letters Patent of the United States No. 783,627, issued to me and dated February 28, 1908, reference 50 thereto being had. As seen in Fig. 2 of the present application said blank is cupped or shaped in an elliptical form 4, having the flanges 5, 6 and 6, with the recess 7 between the flanges 6 and 6, and also provided with 55 the pin catch 8 and the two hinge members or ear pieces 9. Each ear piece 9 has a pivot

hole 10, and a pivot 11 (Fig. 4) extending through both ear pieces 9, in the pivot holes 10 thereof, and engages with the head 12 of a pin tongue 13, the point of said pin tongue 60 being engageable with the pin catch 8, as more fully described in my said Letters Patent. ¶

The collar supporter is attached to the collar, transversely thereof, by means of the pin 65 tongues 13 of the lace pins, which are inserted through the collar at the top and bottom of the same, respectively.

The parts shown in Figs. 1 and 2 are assembled as illustrated in Fig. 4. Each lining 70 plate 2 is laid in the concavity of one of said cupped ornamental fronts 4, between the flange 5 thereof on one side and the flanges 6, 6 on the opposite side. Each end of the bar 1, adjacent to a lining plate 2, integral therewith, extends through the recess 7 of the lace pin 4, as shown in Figs. 4 and 6. The flanges 5, 6 and 6 are then rolled over by any suitable tool to lie in a semi-circular bend 5' and 75 6' with the edges thereof in snug contact 80 with the exposed surface of the back of the lining plates 2, as shown in Figs. 4 and 6.

In Fig. 6 the pin tongue 13 is omitted in order to show more distinctly the relation of the lining plates 2 to the rolled flanges 5' and 85 6' above described.

The innermost ends of the rolled flanges 6' abut the edges of the bar 1 and prevent lateral movement of the lace pins 4 and bar 1 in respect to each other, and so constitute a 90 rigid connection of said parts. This integral construction of the lining plates and the bar of a collar supporter is shown in Fig. 10 of my pending application (Serial No. 416,748) for Letters Patent of the United States, filed 95 February 19, 1908.

In Figs. 3 and 5 is shown a modified form of the device, in which the cupped and flanged ornamental front 14 has two integral rivets 15 formed on the interior surface thereof, which are of such size and diameter as to pass through the rivet holes 3 of the adjacent lining plate 16. This engagement is illustrated in Fig. 5 and the lining plate, in such case is preferably bent, as shown at 17, so as 100 to extend in a plane below that of the flanges 18. The outer end of the rivet 15 is hammered over to form a rivet head in contact with the lining plate 16. The difference between the two constructions is that in Fig. 4 110 the bar 1 and lining plates 2 are held and fastened in the lace pin 4 by the rolled flanges

5', 6' and 6', but in Fig. 5 they are held by the heading of the rivets 15 in the holes 3 of the plates 2. Therefore, in the case of the construction shown in Fig. 4, the rivet holes 5 2 in the plates 2 are dispensed with.

I claim as a novel and useful invention and desire to secure by Letters Patent:—

1. The combination of two concavo-convex lace pins each having a pin tongue; a bar 10 and two lining plates integral with said bar and extending angularly therefrom at opposite ends, each of which plates is adapted to be seated in the concavity of one of said lace pins; and means for fastening said lining plates within said lace pins, respectively.
- 15 2. In a collar supporter, the combination

of two cupped ornamental front plates 4 each having the integral flanges 5, 6 and 6' with the recess 7 between the flanges 6 and 6'; a lining plate 2 held in each cupped plate 4 by the rolled bends of said flanges; a bar 1 integral with both the lining plates 2 and having a width equal to the length of the recesses 7 and engaged in both said recesses; and a pin tongue 13 pivotally mounted upon the rear surface of each of said plates 4.

In testimony whereof I affix my signature in presence of two witnesses.

FRANK E. FARNHAM.
